ROLLING HATCH BEAM ASSEMBLY

John G. Deegan, Bronxville, N. Y.

Application January 18, 1945, Serial No. 573,347

8 Claims. (Cl. 114—201)

1

This invention relates to hatch beams, and more particularly to rolling hatch beams of the type used to support the planking, or hatch covers, for closing the hatches in the various decks of a cargo-carrying ship.

Access to the lower decks of such ships is obtained by means of hatches, usually large rectangular openings, through each successive deck, from an upper deck, known as a shelter, or weather, deck, to the lowermost deck of the ship. On the top deck the opening forming the hatch is ordinarily surrounded by a framing known as the coaming, usually made of steel, which extends a short distance, ordinarily about two or three feet, above the deck level. This coaming serves both to strengthen the deck which has been weakened by cutting the hatch therein, and to prevent water from going down into the vessel. This hatch in the shelter deck is ordinarily closed by planking, or a hatch cover, which rests on beams extending across the hatch. In order to protect the cargo stored below decks, it is, of course, essential that the hatch covers be of solid and substantial construction, and they are therefore usually supported on large I-beams. The hatches in the decks below the shelter deck are covered by planking, so that additional cargo may be carried in these hatch areas. Such planking is also supported by similar I-beams.

Whenever the hatches are to be opened, either in all decks, or in any selected deck, it is usual to remove the hatch covers and the hatch beams by means of hoists and to store these members on the deck of the ship. In this way an opening is provided throughout the vessel for the passage of cargo during the loading and unloading operations.

The removal of the hatch beams in this way is an expensive and time-consuming operation and the storage of the beams on the decks takes up a great deal of valuable deck space, which may be put to better use. Accordingly, it is a primary object of this invention to provide rolling hatch beams of an improved character which may be readily rolled, along tracks supported from the coaming, or hatch siding, to one end, or the other, of the hatch, when it is desired to provide an open hatchway throughout the vessel. Such beams are, of course, rolled back into place before closing the hatchway with the planking, or hatch covers.

As the ends of the hatch beams are normally supported on brackets, or cleats, extending along the hatchways, it is another object of this invention to provide means whereby the hatch beams

2

may be raised from their normal, or resting, positions, and supported on the tracks during the operation of rolling them to one side of the hatch opening to provide an open hatchway. These same means permit lowering of the I-beam back to resting position on the cleats. In this position the rollers from which the beams are supported during rolling operation rest on the tracks, but carry only their own weight.

10 It is a further object of this invention to provide means for elevating, or lowering, the hatch beams, and for rolling them to one side, or back into place, preparatory to closing the hatch, which means are of an improved character in that they do not include the customary levers, or other operating mechanism, projecting into the hatch which interferes with loading, or unloading, operations as well as with the proper positioning of the hatch covers in place at the 15 various deck levels. In effecting this object of the invention, means are used for lifting the hatch beams from their normal supporting positions to the rollers traveling on the tracks, or for lowering the hatch beams so that their weight 20 is taken off the rollers and supported on the cleats, which lifting means are readily operated by a bar inserted in an opening provided in a capstan head of the lifting and lowering element. This bar is inserted in the capstan head only during 25 the actual lifting or lowering operation, so that it does not project at other times into the hatch.

Still another object of this invention is to provide a track for the rollers on which the rolling 30 hatch beam is supported during the operation of moving the beam, which track is readily secured either to a horizontal coaming, or a vertical coaming, thereby permitting its use at the 35 various deck levels throughout the ship. Moreover, the track is so arranged that the upper part thereof is at the same level as the top surface of the hatch beams thus permitting the placing of the planking, or hatch cover, across both the 40 hatch beams and the track. In this way the track aids in supporting the hatch cover when 45 the hatch is closed.

Other objects and advantages of the invention will be apparent from the ensuing disclosure, taken in connection with the appended drawings, 50 wherein:

Fig. 1 is an elevational view showing two of the rolling hatch beams arranged one above the other as they might be arranged at the shelter and lower decks, respectively;

Fig. 2 is an enlarged elevational view, partly

in section, of the right hand end of one of the beams illustrated in Fig. 1, showing the supporting track and the roller arrangement;

Fig. 3 is a plan view of the parts shown in Fig. 2;

Fig. 4 is a cross-sectional view taken substantially along the line 4—4 of Fig. 2;

Fig. 5 is a vertical cross sectional view through the elevating means by which the end of the hatch beam may be elevated from its normal, or resting, position so that it is supported from the track, or lowered from the track back upon its normal support, this view being taken along the line 5—5 of Fig. 2;

Fig. 6 is a vertical cross-sectional view taken on the line 6—6 of Fig. 2;

Fig. 7 is a partial elevational view of a modified form of beam-lifting means; and

Fig. 8 is a cross-sectional view taken substantially along the line 8—8 of Fig. 7.

Referring more specifically to the general arrangement shown in Fig. 1, the rolling hatch beams are denoted generally by the numeral 11 and may be of I-beam shape with web 12 and upper and lower flanges 13 and 14. At each end of the I-beam there are provided doubler plates 15, preferably on each side of the beam web, as shown in Fig. 6. These plates, together with the beams, may be cut away at certain portions as shown for example in Fig. 1, or in any suitable manner, in order to provide the necessary clearances between the hatch beam and the brackets, or cleats, normally supporting it. The two rolling beam constructions illustrated in Fig. 1 are adapted to show how the track is positioned and the hatch beams supported therefrom when the coaming is horizontal, as illustrated in the upper part of the figure, and when the coaming is vertical, the track in this case being supported directly from the sides of the hatchway, as illustrated in the lower part of the figure.

Plates 15 have flanges 19 which normally rest on the cleats 21 attached to the hatchway siding or coaming 17. While these supports are shown as having the cross-sectional shape of a quadrant of a circle, it is, of course, possible to use supporting means of other shapes and, for convenience, in many cases ordinary angle members might be employed. If desired, "sockets" may be provided for the beams to rest in, by welding or otherwise attaching, strips 19a on the cleats 21 adjacent the resting positions of the beams.

As shown in Fig. 1, tracks 23 are provided for rollers 24 so that the hatch beams may be supported from the tracks along which the rollers 24 are adapted to roll, or slide, during the operation of moving the hatch beams to one side to provide an open hatchway, such as is necessary when loading, or unloading, the cargo. The track 23 may be conveniently formed in the shape illustrated, and may be constructed of sheet metal, the shape depending to some extent on whether the coaming to which it is secured by welding, or otherwise, is horizontal or vertical. A preferred design of track is disclosed in greater detail and claimed in copending application Serial No. 570,196, filed December 28, 1944, now Patent No. 2,435,190, dated February 3, 1948.

As shown in the upper part of Fig. 1, the lower edge of the track 23 is secured, by welding, or otherwise, to horizontal coaming 18, while its upper edge is secured to a vertical coaming 26. This vertical coaming may, of course, be the hatch siding where the rolling hatch beam is lo-

cated at a deck lower than an upper, or shelter, deck of the ship. Thus, in the construction illustrated in the lower part of Fig. 1, the track 23 is welded, or otherwise secured, at both its upper and lower edges, to the vertical coaming, or vertical hatch siding 17. In both cases, the rollers 24 are adapted to roll in a track 23 so shaped as to accommodate these rollers and to prevent the rollers from jumping the track.

The arrangement by which the ends of the rolling hatch beam 11 may be elevated, or lowered, so that the weights of the beams may be transferred from the supports 21 (Fig. 1) to the rollers 24, located in the track 23, and back to the supports, is shown more particularly in Figs. 2, 3 and 5.

Referring first to Fig. 3, it will be noted that the rollers 24 are rotatably supported in a roller carriage 28. A preferred arrangement of supporting these rollers is shown as comprising a roller pin 29 having a threaded portion 29a screwed into the member 28 and an enlarged head 30 provided with the usual screw slot 30a into which a screw driver may be fitted. Between the main body portion of the pin 29 and the roller 24, a suitable bushing 31 is interposed. The pin 29 is held against rotation by means of locking pins 31a which extend through the member 28. As shown in this figure, there may be provided at each end of the rolling hatch beam 11, two rollers 24, although, of course, one roller might be utilized, or the number of rollers might exceed the two illustrated. The number of rollers may be largely determined by the load which is to be transmitted through the rollers 24 to the track 23.

Referring now more particularly to Fig. 2, the roller carriage 28 is provided with a laterally extending portion 33, having a cylindrical aperture through which an elevating and lowering member, hereinafter described, is adapted to pass. The carriage 28 has a guide pin 32 extending through it and into an underlying worm nut block 41 so as to prevent turning of the member 28 about the axis of the elevating and lowering member which would cause the rollers 24 to jam in the track 23. The pin 32 may be held in position by a set screw 32a in the member 28.

As shown more clearly in Figs. 2 and 5, this elevating and lowering member is formed with an operating hub 36 of capstan type, having a depending portion 44 projecting into the portion 33 of the carriage 28. The hub 36 has a drilled hole 38 for seating a turning bar 39 when the screw is to be turned in order to raise, or lower, the end of the rolling hatch beam. The depending portion 44 of the screw head 36 is secured to a shank 43 by means of a pin 42 so that rotation of the hub 36 as previously described causes the shank 43 to rotate.

The shank 43 is provided at its lower end with screw-threaded portion, or worm, 40, of large pitch, coacting with a nut 41, which is secured by suitable means, presently to be described, to the end of the rolling hatch beam 11. The worm 40 is secured to the shank 43 by a key 43a (Fig. 5). The lower end of the shank 43 is screw threaded so that a nut 47 may be secured thereto below the worm 40 to prevent the latter from coming off the shank. Washers 45 and 46 may be positioned between the hub 36 and the portion 33 of carriage 28, and the portion 33 and worm 40, respectively, to provide a tight assembly for the elevating and lowering mechanism.

As shown in Figs. 3 and 5, the hub 36 may be

somewhat eccentric with respect to the center line of the lifting mechanism, thereby providing a longer bearing surface for the turning bar 39 in the aperture 38 during the raising and lowering operations.

The nut 41 through which the worm 40 passes, is constructed with a laterally extending portion 50 (Figs. 2 and 4) having an aperture through which the guide pin 32 passes and in which it slides freely during the raising and lowering movements of the elevating mechanism.

A preferred arrangement for connecting the nut 41 with the hatch beam 11 for raising or lowering the same, will now be described. As shown clearly in Figs. 4 and 5, this nut may be secured to a channel 53. A portion of the top flange of this channel is cut away adjacent the nut 41, as shown at 53a in Figs. 3 and 5, to provide the clearance necessary to permit relative movement of the laterally extending portion 33 of carriage 28.

The channel 53 is slidably associated with the hatch beam and is urged toward the opposite end of the beam so that the nut 41 and its associated lifting mechanism carrying the rollers 24 will tend to pull these rollers away from the vertical wall of the track 23, thereby minimizing the tendency of the rollers to jam in the track if the beam becomes skewed while being rolled during the opening, or closing of the hatch.

As shown in Figs. 3 and 4, nuts 64 and 65 may be welded to the doubler plate 15. Preferably these two nuts are also welded to a spacing member 66 prior to being secured to the doubler plate to facilitate accurate location of the nuts. The bolts 57 are threaded into these nuts, and pass through elongated slots 55 and 56 in the channel 53. Washers 60 may be interposed between the bolt heads 58 and the channel. A locking pin, or rod, 62 prevents the bolts 57 from being loosened. It will be noted that with this arrangement, the channel 53 is bolted to the hatch beam in such manner as to permit the channel to move longitudinally with respect to the hatch beam.

As shown in Figs. 3 and 4, the channel 53 is normally urged to the left by means of springs 72 abutting against an upturned portion 70 on the channel and against a stop plate 69, which may be secured to the lefthand nut 64. While two springs 72 are shown in the embodiment illustrated, one spring might be employed or, if desired, more than two may be used.

The operation of the rolling hatch beam construction illustrated and described may be explained as follows:

Normally the hatch beam rests in sockets in the cleats 21. The rollers 24 are in contact with the track 23 but are supporting only their own weight. In this condition, the top flange 13 of the hatch beam 11 is substantially at the same level as the upper portion of the track 23, whereby the track and flange 13 of the I-beam 11 may both be used to support the planking, or hatch cover, used to close the hatch.

When it is desired to roll the hatch beam to one side in order to provide an open hatch for the loading or unloading of cargo, operating bar 39 is inserted in opening 38 in the hub 36 of the elevating and lowering mechanism and the worm 40 is caused to turn with respect to the nut 41. In this way the nut 41 is raised with reference to the extending flange 33 of carriage member 28, to which are secured the rollers 24, the guide pin 32 sliding freely in the aperture in the ex-

tending portion of the nut 41. Since the nut 41 is secured by welding, or otherwise, to the channel 53, which, in turn, is secured by bolts 57 to the hatch beam 11, the end of the hatch beam 11 is also raised with reference to the rollers 24. As a result, the weight of the beam is borne by rollers 24 and track 23. When both ends of the hatch beam are thus raised, it is possible to roll the beam to one side of the hatch along the tracks 23, and when all the hatch beams are thus rolled to one side, the hatch is open for loading, or unloading cargo.

When it is desired at the completion of the loading, or unloading, operation, or at other times, to return the I-beams to their normal position intermediate the end of the hatchway, the I-beams are first rolled to position above their resting places. The lowering mechanism is turned, so that the nut 41, channel 53, and the adjacent end of the I-beam are lowered with respect to extending flange 33 of the carriage member 28 to which the rollers 24 riding on track 23 are secured, until the beams seats on the cleats 21.

The modified form of raising and lowering mechanism shown in Figs. 7 and 8 differs from the form previously described in that instead of using a worm and coacting nut, it employs two camming surfaces. These are the surfaces which raise and lower the end of the hatch beam according to the direction of movement of these surfaces with respect to each other. As shown more particularly in Fig. 8, a member 75 is bolted to the channel 53 by means of bolts 76 and is provided on its underside with a camming surface 77. The cooperating camming surface 78 is formed on a sleeve 79 which may be keyed, or otherwise secured, to the lower end of a bolt 80, threaded into the extension 33 of the carriage member 28. Thus when the operating hub 36 is rotated by means of the turning bar 39, the bolt 80 causes the sleeve 79 to rotate so that its camming surface 78 cooperates with the camming surface 77, thereby causing the member 75 and its associated channel and beam end to be raised or lowered.

It is to be understood that this invention is not confined to the exact details of construction shown and described herein since various modifications may be made by those skilled in the art without departing from the spirit and scope of this invention.

I claim:

1. In combination with a hatchway having coamings, and supports for hatch beams, along opposite sides, a hatch beam adapted to rest on said supports, tracks supported by the hatch coamings, a plurality of rollers at each end of the beam and adapted to roll along said tracks and mechanisms for raising and lowering said beam from and to its support, each of said mechanisms comprising a member slidably mounted on said beam but adapted to move vertically with said beam, a support for said rollers, means rotatably engaging said member to effect displacement thereof with respect to the roller support, and means for preventing angular displacement of said rollers with respect to said beam.

2. In combination with a hatchway having coamings, and supports for hatch beams, along opposite sides, a hatch beam adapted to rest on said supports, tracks supported by the hatch coamings, roller means adapted to roll along said tracks and mechanisms for raising and lower-

ing said beam from and to its supports, said mechanisms each comprising a member slidably secured to said beam, a roller carrying member, means rotatably associated with said roller carrying member and engaging said first-named member to effect displacement thereof with respect to the roller carrying member; and resilient means tending to bring said slideable members on opposite ends of the hatch beam together to prevent binding of the beam.

3. In combination with a hatchway having coamings, and supports for hatch beams, along opposite sides, a hatch beam adapted to rest on said supports, tracks supported by the hatch coamings, a plurality of rollers at each end of the beam adapted to roll along said tracks, and mechanisms for raising and lowering said beam from and to said supports, said mechanisms each comprising a slideable member connected with said beam, a support for said rollers, means rotatably engaging said member to effect displacement thereof with respect to the roller support, means for preventing said rollers from being angularly displaced with respect to said beam, and resilient means normally urging the rollers at the opposite ends of the beam toward each other to prevent binding of the rollers in said tracks.

4. In combination with a hatchway having coamings, and supports for hatch beams, along opposite sides, a hatch beam adapted to rest on said supports, tracks supported by the hatch coamings, rollers adapted to roll along said tracks and mechanisms for raising and lowering the said beam from and to its supports, said mechanisms each comprising a member slidably supported on said beam, a nut attached to said member, a support for said rollers, means rotatably engaging said member to effect displacement thereof with respect to the roller support, said means and roller-supporting member being supported from said nut, and resilient means normally urging said slideable member toward the beam whereby the rollers on the opposite ends of the beam tend to approach each other to prevent binding of the rollers in the track.

5. In combination with a hatchway having coamings, and supporting sockets for hatch beams, along opposite sides, a hatch beam adapted to rest in said sockets, tracks supported by said coamings, rollers adapted to roll along said tracks and mechanisms for raising and lowering said beam from and to its supports, said mechanisms each comprising a member secured to said beam, a support for said rollers, means rotatably engaging said member to effect displacement thereof with respect to the roller support, and a locking pin connected to the support for said rollers and slidably associated with the first-named member to prevent angular displacement of the rollers with respect to the beam to prevent said rollers from binding on the track.

6. In combination with a hatchway having coamings, and supports for hatch beams, along opposite sides, a hatch beam, trackways supported by said coamings, rollers adapted to travel on said trackways, and beam elevating and lowering mechanisms positioned between said hatch beam and rollers, each of said rollers being attached to an end of said hatch beam through said elevating and lowering mechanisms, each of said mechanisms comprising a member to which

said rollers are attached, said member provided with a depending pin and with an apertured portion; an elevating and lowering element passing through said apertured portion and provided with a screw-threaded portion; an internally threaded socket for seating said screw-threaded portion, said socket being secured to an attachment member secured to said hatch beam and provided with an apertured flange through which said pin is adapted to move axially, whereby when said element is rotated said hatch beam is raised or lowered with respect to said rollers and said trackways.

7. In combination with a hatchway, having coamings, and supports for hatch beams, along opposite sides, a hatch beam, trackways supported from said coamings, roller means adapted to travel along said trackways, and beam elevating and lowering mechanisms positioned between said hatch beam and said roller means, each of said roller means being attached to an end of said hatch beam through said elevating and lowering mechanisms, each of said elevating and lowering mechanisms comprising a member to which said roller means is attached, said member being provided with a laterally extending apertured portion; a rotatable element passing through said apertured portion and provided, at one end thereof, with a rotatable hub, and at the other end with a screw-threaded portion; a threaded member adapted to engage said screw-threaded portion, said threaded member being secured to an attachment member provided with a plurality of slots; a plurality of nuts secured to said hatch beam; a plurality of bolts passing through said slots and engaging said nuts, whereby when said rotatable hub is rotated, it is raised or lowered with reference to said threaded member, thereby raising or lowering said hatch beam with respect to said roller means and said trackways.

8. In combination with a hatchway having coamings, and supports for hatch beams, along opposite sides, a hatch beam adapted to rest on said supports, tracks supported by the hatch coamings, rollers adapted to roll on said tracks and mechanisms for raising and lowering said beam from and to its support, each of said mechanisms comprising a member slidably secured to the end of said beam and adapted to raise and lower said beam when it is raised or lowered, roller-supporting means, a rotatable element engaging last said means; said member and element having cooperating camming surfaces whereby relative rotation therebetween raises or lowers said beam; and resilient means urging said member away from the track to reduce roller jamming.
